(57) **CLAIM**

An ornamental design for a saw guard, as shown and described.

DESCRIPTION

FIG. 1 is an isometric view of a saw guard connected to a riving knife and saw table for illustration purposes. The riving knife and saw table are shown in dashed lines for environment.

FIG. 2 is a top isometric view of the saw guard of FIG. 1 with the riving knife and saw table removed.

FIG. 3 is a bottom isometric view of the saw guard of FIG. 1.

FIG. 4 is a top plan view of the saw guard of FIG. 1.

FIG. 5 is a bottom plan view of the saw guard of FIG. 1.

FIG. 6 is a front elevation view of the saw guard of FIG. 1.

FIG. 7 is a rear elevation view of the saw guard of FIG. 1.

FIG. 8 is a left side elevation view of the saw guard of FIG. 1; and,

FIG. 9 is a right side elevation view of the saw guard of FIG. 1.

The dashed lines in FIG. 1 illustrate environment consisting of a riving knife and saw table that form no part of the claimed design. The remaining dashed lines in FIGS. 2-9 illustrate portions of the saw guard that form no part of the claimed design.
